CHARGE FORMER

Theodore A. Ormsby, San Antonio, Tex.

Application December 7, 1939, Serial No. 308,090

2 Claims. (Cl. 137—139)

This invention relates to a charge former.

An object of the invention is to provide efficient and novel means for furnishing a continuous supply of fuel in gaseous form for internal combustion engines, and the like.

Another object is to afford facilities for the proper control of the fuel supply and to provide efficient means for conservation of gasoline consumption.

A still further object is to provide novel means that work in combination with the regular form of carburetion and means that will provide automatically a gaseous form of fuel.

With the foregoing and other objects in view, the invention comprises certain novel constructions, combinations, and arrangements of parts as will be hereinafter fully described, illustrated in the accompanying drawings, and more particularly pointed out in the appended claims.

In the drawings:

Figure 1 is a view partly in side elevation and partly in longitudinal section of a charge former constructed in accordance with the present invention.

Figure 2 is an enlarged front view in elevation of the two-way valve of the thermostatic valve mechanism, while

Figure 3 is an enlarged sectional view taken on line 3—3, Figure 1, and looking in the direction of the arrows.

Figure 4 is an enlarged sectional view taken on line 4—4, Figure 1, and looking in the direction of the arrows.

Figure 5 is an enlarged sectional view taken on line 5—5, Figure 1, and looking in the direction of the arrows.

Figure 6 is a sectional view taken on line 6—6, Figure 3, and looking in the direction of the arrows.

Referring to the drawings by numerals, 1 designates the exhaust manifold and 2 is the carburetor. The carburetor 2 is provided with a neck 3, a butterfly valve 4 and a control arm 5. Connected at 6 to arm 5 is an accelerator rod 7, which rod 7 is operated in the usual manner.

A copper pipe 8 extends through the exhaust manifold 1 for a portion of its length and has its outer end suitably connected to and communicating with the interior of neck 3 of the carburetor 2. The inner end of the pipe is bent laterally and extended to an opening in the side wall of the manifold so that air may enter the pipe. This copper pipe 8 constitutes a heating unit for facilitating the production of gas from

the gasoline supplied to the mechanism. A suitable covering 9 is placed on the pipe 8, outside of the manifold 1 to prevent cold air from hitting the pipe, between the exhaust manifold and the carburetor. The exhaust manifold 1 is provided with an exhaust opening 10, Fig. 4.

Mounted on the exhaust manifold 1 and copper pipe 8 is a manifold valve device 11 (Fig. 4). This valve device 11 comprises a primary housing 12 mounted on pipe 8, and threaded into the primary housing 12 is an auxiliary housing 13. A cap 14 is threaded upon the outer end of auxiliary housing 13. A sleeve 15 is threaded through cap 14, and on the inner end of sleeve 15 is a threaded adjustable cap 16; cap 16 is provided with a valve seat 17. The sleeve 15 has an outer threaded end 17'; this end 17' is internally and externally threaded. Mounted on the threaded end 17' is a packing containing nut 18. Extending through nut 18 and sleeve 15 is a needle valve 19. This needle valve is threaded through end 17' as shown, with its inner end working through valve seat 17. By adjusting cap 16 longitudinally of sleeve 15, a very nice adjustment can be obtained, for accurately controlling the flow of gasoline, or like substance into copper pipe 8. The outer end of the needle valve carries a lever arm 20 which extends downwardly and has its lower end pivoted to a link 21 by means of which it is connected with the rod 7. When the rod 7 is moved to adjust the butterfly valve 4, turning movement will be imparted to the needle valve and since the needle valve is threaded through the outer end of the sleeve 15, the needle valve will be adjusted at the same time the butterfly valve is adjusted. The extent the needle valve is opened or closed during movement of the rod 7 is controlled by the length of the arm 20. The shorter the arm 20 is the greater the opening or closing movement of the needle valve will be. It will thus be seen that the two valves will be simultaneously adjusted and that proportionate opening and closing of the valves will be controlled.

45 A thermostatic valve mechanism 22 is provided, comprising a supporting frame 23. Supporting frame 23 includes a flat base 24 with an auxiliary upright end 25 and a primary upright end 26. The base 24 rests upon a flat seat 27 on the manifold 1. A bushing 28 extends through the horizontal base 24 and into the exhaust manifold, whereby the supporting frame is held securely in position. A lever rod or bar 29 is pivotally mounted on pin 30; pin 30 is mounted in eyes 31, that are formed upon the

upper end of the auxiliary upright 25, Fig. 5. This pivotally mounted bar 29 is over a thermostat or expansion copper rod 32. Rod 32 is slidably mounted in the bushing 28 with its inner end normally engaging the interior of the exhaust manifold 1, and its outer end engaging the under face of the rod or bar 29. A coil spring 33 is connected at one end to bar 29 and at its outer end to base 24, to normally exert an inward pull upon the rod or bar 29. A V-shaped link 34 is pivotally mounted at 35 upon upright end 26 of the supporting frame. The lower or inner portion of link 34 is provided with a yoke 36, in which the inner end of bar 29 slides. A coil spring 37 is fastened at its outer end to yoke 36 and its inner end is fastened to upright 26. Secured upon upright end 26 is a valve casing 38 (Fig. 6), which valve casing is preferably threaded into said upright end 26, for securely holding said casing in position. Valve casing 38 is provided with a rotary cylindrical valve 39. Valve 39 is provided with an annular groove 40 into which extends the inner end of set screw 41, whereby the rotary valve is held securely within casing 38. A fixed arm 42 is secured to the valve 39, and a control lever 43 is pivotally connected at its outer end to arm 42 and at its inner end to the outer end of the V-shaped link 34, whereby when link 34 is pivoted at 35, movement will be imparted to the rotary valve 39. Rotary valve 39 is provided with three ports, Fig. 3. When the valve is in the position shown in Fig. 3, the fuel, such as gasoline, can enter through the main inlet pipe 44; pipe 44 being connected to the fuel pump 45, and supply pipe 46 is also connected to said pump. After entering the rotary valve, the gasoline will pass directly to the carburetor through pipe 47. When starting the motor, the gasoline, or other suitable fuel, will pass from the fuel pump into the two-way valve and thence directly to the carburetor, through pipe 47. When the motor has sufficiently heated to actuate the thermostat rod 32, said rod will expand, exerting pressure on the rod or bar 29. Bar 29 is held tight against rod 32 by spring 33; spring 33 also holds bar 29 down when rod 32 contracts. Therefore, when rod 32 cools and contracts sufficiently the pull of spring 33 trips V-shaped link 34, throwing valve 39. The farthest end of bar 29 rests between the jaws 36 of the V-shaped link 34. There is enough clearance between these jaws that the long end of bar 29 does not contact the upper jaw until thermostat rod 32 has actuated sufficiently. Having done so, the outer end of bar 29 contacts the upper jaw 36 of the V-shaped link 34, exerting a pressure thereon. This pressure puts link 34 off center. Link 34 pivots at 35. Coil spring 37 takes advantage of this pivoting action at 35 and instantly throws V-shaped link 34 completely over, thereby rotating valve 39 instantly, whereupon the pipe 47 will be closed, and the ports of the rotary valve will register with the inner ends of the main inlet pipe 44 and the pipe 48, which pipe 48 communicates at its lower end with the airdome 49.

The clearance between these jaws 36 of 34, takes care of the slow expansion and contraction of the rod 32, and coil spring 37 instantly takes care of the throwing of the valve 39.

There will be sufficient gasoline in the carburetor bowl to supply the engine while gasoline injected into pipe 8 could reach the carburetor. Likewise, there would be sufficient gasoline in pipe 8, valve 11 and airdome 49 to supply the en-

gine while gasoline entering pipe 47 reaches the carburetor. Then, from the airdome 49, the gasoline is passed through pipe 50 to the interior of sleeve 16, Fig. 4. The airdome 49 is supported upon angle bracket 51; this bracket 51 is secured at its inner end in any suitable manner to the supporting frame 23, Fig. 1.

The airdome 49 acts as a shock absorber to gasoline line 48 and 40. It also forms a reservoir 10 for gasoline to back up into; said gasoline being forced out by the compressed air in airdome 49 after flow of gasoline from 44 to 48 is stopped, thus furnishing sufficient gasoline for the engine over the period that it takes gasoline entering 15 47 to reach the carburetor.

It is to be understood that when the motor is sufficiently warm, that the direct flow of gasoline to the carburetor will be stopped, and that the gasoline will be directed by the thermostatic 20 valve mechanism to the airdome, wherein the gasoline is supplied with pressure and thence passed to the manifold valve device, to be heated into a highly efficient gas state, prior to entering the carburetor.

25 I use the word "pipe" in this specification and the appended claims in a broad sense, meaning any suitable pipe, tube, or conduit.

While I have described the preferred embodiment of my invention and illustrated same in the accompanying drawings, certain changes or alterations may appear to one skilled in the art to which this invention relates during the extensive manufacture of same, and I, therefore, reserve the right to make such changes or alterations as shall fairly fall within the scope of 30 the appended claims.

What I claim is:

1. In a thermostatic valve mechanism, a frame 40 having a base and main and auxiliary uprights rising therefrom in spaced relation to each other, a rod mounted through the base adjacent the auxiliary upright and formed of material adapting it to changes in length in response to variations in temperature, a lever bar pivoted at one end to the auxiliary upright and extending towards the main upright in spaced relation to the base and resting upon the upper end of said rod, a valve including a casing secured to the main upright and a rotary valve member in the casing having a stem extending from the casing and provided with a laterally extending arm, a link pivoted to said arm and extending therefrom, and a bell-crank lever pivoted to the main upright with one arm pivoted to the lower end 45 of said link, and its other arm extending towards the lever bar in spaced relation to the base and terminating in a yoke loosely receiving the free end of the lever bar to provide a lost motion connection between the lever bar and the bell crank lever.

2. In a thermostatic valve mechanism for a charge former, a frame having a base and main and auxiliary uprights extending upwardly from opposite ends thereof, the main upright being appreciably taller than the auxiliary upright, a hollow fastener threaded through the base adjacent the auxiliary upright for securing the frame upon an exhaust manifold of an engine, a rod mounted through said fastener with its outer portion projecting therefrom, said rod being formed of material adapting it to changes in length in response to variations in temperature, a lever bar pivoted at one end to the upper end 70 of the auxiliary upright and extending towards the main upright over the base, a spring yield-

ably holding the lever bar in engagement with the outer end of the rod, a valve including a casing fixed to the upper portion of the main upright and a rotary valve member in the casing having a stem provided with a side arm, a link pivoted at its upper end to the outer end of the side arm, a bell crank pivoted to the main upright below the valve and having one arm extending at an upward incline and pivoted to the lower end of said link, the other arm of the 10

bell crank extending longitudinally of the base in spaced relation thereto and terminating in a yoke loosely receiving the free end of the lever bar, and a spring extending longitudinally of the lower arm of the bell crank and secured at one end to the main upright and at its other end to the yoke and serving to yieldably control pivotal movement of the bell crank.
